(57) **CLAIM**

The ornamental design for a candle cover, as shown and described.

DESCRIPTION

FIG. 1 is a perspective view of the top, side, and front of my new design for a candle cover.

FIG. 2 is a front elevation view of my new candle cover.

FIG. 3 is a rear elevation view of my new candle cover.

FIG. 4 is a top plan view of my new candle cover.

FIG. 5 is a bottom plan view of my new candle cover.

FIG. 6 is a right side elevation view of my new candle cover; and,

FIG. 7 is a left side elevation view of my new candle cover.

The broken line showing of the wicks in FIGS. 1 and 4 is for illustrative purposes only and forms no part of the claimed design.
